GRINDING MACHINE

Frederick S. Haas, Cincinnati, Ohio, assignor to
Cincinnati Grinders Incorporated, Cincinnati,
Ohio, a corporation of Ohio

Application October 4, 1937, Serial No. 167,216

12 Claims. (Cl. 51—105)

This invention relates to improvements in grinding machinery and has particular reference to that type of machine shown in Patent 2,025,885.

5 One of the principal objects of the present invention is the provision of an improved simplified manual control for the various movements of the machine.

A further object of the invention is the provision of an improved semi-automatic machine of 10 this character for effecting sequential clamping, rapid infeed and subsequent controlled final feeding movements in an extremely simple and efficient manner.

15 A further object of the invention is the provision of a control mechanism which shall include a lost motion device permitting clamping of the work at the initiation of the control movements and a delayed unclamping or release of the work 20 effective subsequent to initial retraction of the grinding wheel.

A further object of the invention is the provision 25 of a single lever control mechanism of this character which will effect successive clamping and unclamping of the work in predetermined positional sequence and concurrently with, or independently of, the operation of the feeding movement for effecting the grinding operation.

An additional object of the present invention 30 is the provision of an improved control mechanism for valve devices for effecting certain movements of a grinding machine, such as the work clamping and rapid traverse movements which will actuate the valves in reversed sequence during relative approach and retraction of the work 35 and grinding element.

Other objects and advantages of the present invention should be readily apparent by reference to the following specification, considered in 40 conjunction with the accompanying drawings forming a part thereof and it is to be understood that any modifications may be made in the exact structural details there shown and described, within the scope of the appended claims, 45 without departing from or exceeding the spirit of the invention.

Figure 1 is a plan view of a machine embodying the present invention.

Figure 2 is a sectional view as on the line 2—2 50 of Figure 1.

Figure 3 is a diagrammatic view of the several controls for the machine.

Figure 4 is an enlarged sectional view illustrating the valves and operating mechanism therefor 55 as on the line 4—4 of Figure 2.

Figure 5 is a fragmentary sectional view as on the line 5—5 of Figure 2.

Figure 6 is a fragmentary view illustrating the position occupied by the control elements when effecting clamping of the work. 5

Figure 7 is a view corresponding to Figure 6 showing the position occupied by these parts during the grinding operation.

In the drawings in which similar characters of reference are employed to denote similar or corresponding parts:

The numeral 10 designates the bed of the machine having ways 11 for the work chuck carriage 12 having rotatably mounted thereon the table 13 supporting the suitably driven chuck 15 15 for reception of a work piece 16. It will be noted that the chuck and its supporting spindle may be angularly adjusted about swivel mounting 17 to determine the angle of presentation of the periphery of the work to the grinding wheel 18, 20 and, in addition, may be given a bodily adjustment toward and from the grinding wheel to accommodate different sizes of work or to compensate for wheel wear as by the lead screw 19 and pilot wheel 20. Pivotally supported by the 25 right hand portion of the bed, as viewed in Figures 1 and 2, for oscillation about a trunnion axis at 21 is the grinding wheel head 22 supporting spindle 23 on which is mounted the wheel 18.

It will be noted that the weight of the wheel 30 head 22 is to the right of the pivot, therefore tending to swing the head downward and moving the wheel into retracted position as respects the work piece 16. Two cooperating mechanisms are provided for effecting oscillation of the wheel 35 head in the opposite direction. The first of these comprises a cylinder 24 having slideable therethrough the plunger 25 provided with an intermediate piston portion 26. Conduits 27 and 28 coupled with opposite ends of the cylinder permit 40 respectively introduction of suitable pressure medium through line 27, to the top of the cylinder, depressing the plunger while the fluid from the lower portion of the cylinder is exhausted through line 28, or alternatively an introduction of pressure into line 28 with concomitant exhaust through line 27 causing a positive raising of the plunger. 45

Contacting the lower end of the plunger 25 is a second plunger 29 having a roller 30 riding on 50 cam 31 carried by shaft 32 journaled in the bed on suitable anti-friction bearings and extending to the front of the machine where it is provided with the manually actuatable handle 33. From the foregoing it will be seen that cam 31 through 55

the elements 30 and 29 takes up the reaction of plunger 25 so that on introduction of pressure into the upper end of cylinder 24, the cylinder actually will be raised—the plunger remaining stationary. This raising of the cylinder causes a tilting of the head 22, moving the grinding wheel rapidly in the direction of the work piece 16.

Additional oscillation of shaft 32 by operation of handle 33 in a counterclockwise direction will 10 oscillate cam 31, imparting movement as an entirety to the combined plunger 29—25. As the pressure in the upper end of the cylinder is sufficient to maintain piston 26 and plunger 25 depressed or at the bottom of cylinder 24, this 15 action of the cam serves to impart a slow or manually controlled infeed movement to the grinding wheel for effecting the desired stock removal. The extent of such movement may be suitably controlled either by an automatic gaging device, 20 a mechanical stop as at 34 for limiting the movement which can be imparted to lever 33, or by visual size determination and discontinuance of the infeed when the work has been reduced to a proper point. A particular mechanism for accomplishing the latter result has been illustrated 25 in connection with Figures 1 and 3 comprising a gaging member 35 adapted to contact the work during grinding and cooperating with a dial 36 actuatable to indicate when the work has been reduced to proper size. This mechanism, as an entirety, is carried by a swinging bracket 37 automatically actuated into and out of position for the gage point 35 to contact the work as by a suitable piston cylinder or hydraulic motor, designated 30 as an entirety by the numeral 38.

The particular manner of controlling the cyclic sequential operation of these various elements will probably best be understood by reference to Figures 3 and 4. While there has been illustrated 40 what, up to the present time, has been found to be the most efficient satisfactory embodiment in that two independent sources of pressure fluid for actuation of the parts are employed, it is to be understood that if desired these could be combined.

As there illustrated, use is made of a sump 40 from which suitable hydraulic medium is drawn by pump 41 and discharged into pressure line 42 having one branch leading to the control valve 45 casing 49 and a second branch 44 extending to the valve casing 45. With the machine in the idle or non-grinding position, as there shown, conduit 44 is coupled by port 46 and valve spool 47 to conduit 28 leading to the lower end of cylinder 55 24 so that plunger 25 is in raised position. At the same time, 42 is coupled with pressure groove 48 of valve casing 49, and thence, in the position of the parts shown, through resistance 50 to lines 51 and 52, line 51 being at present blocked. The 60 pressure differential normally created by resistance 50 when there is flow through 51 no longer exists. Consequently, full pump pressure will be build up in line 52 reacting on escape valve 54 against the pressure of spring 55, tending to move 65 this valve to the right, opening up communication between line 42 and reservoir connection 56, and thence through resistance 57 which maintains a prescribed back pressure into the reservoir 40.

At the same time, compressed air or other fluid 70 actuating medium is supplied from source 60 to valve casing 61 by way of cannelure 62 of valve 63 and conduit 64 to the rear of left hand pressure port 65 of the chuck control mechanism, where it is introduced by channel 66 to the rear of piston 67. Piston 67 has its rod 68 terminating in a head

69 engaging the clamp devices 70, which due to their angular position in the work chuck head 71 are drawn together, interiorly disengaging themselves from the work piece.

With the parts in the position just described, as 5 handle 33 is oscillated in a counterclockwise direction, rock arm 72 which is frictionally secured to move with shaft 32 by the opposed clutch members 73 and 74, urged toward each other by spring 75, will be oscillated also in a counterclockwise 10 direction or with its lower portion, as viewed in Figure 5, moving toward the right. This arm has adjustably secured to it as by the bolt 76 a second section 77 carrying the cross pin 78, engaged in the elongated notches 79 and 80 of the 15 valve members 63 and 81 respectively.

It is to be noted that valve member 63 is actuated downwardly, as viewed in Figure 4—or correspondingly, to the right as viewed in Figure 3 by the tension spring 82. Consequently, as pin 20 77 is shifted by oscillation of arm 72, the spring will cause immediate follow-up of valve 63, while due to the elongation of the notch 80 the position of valve 81 which is urged upwardly as viewed in Figure 4, or to the left as viewed in Figure 3, by 25 the compression spring 83 will remain unchanged.

When the parts have reached their first phase of movement, as indicated in Figure 6, valve 63 under the influence of its spring will therefore have been completely shifted, coupling pressure 30 source 60 with conduit 84 extending to the right hand side of piston 67 causing a retracting movement of head 69 and arms 70, clamping work piece 16 in position on the work head or chuck 15.

Continued movement of lever 33 will then cause 35 reaction of pin 78 against valve 81, shifting this valve against force of spring 83. This shifting of valve 81 will then couple pressure line 44 through cannelure 85 with conduit 27 leading to the upper portion of cylinder 26, thereby raising 40 the cylinder rapidly to cause a rapid traverse or infeed of the grinding wheel with respect to the work piece now firmly held on and rotating with the work head. Continued movement of handle 33 in a clockwise direction effects a continuing 45 advance of cam 31 which is rigidly secured on the shaft. Due, however, to the fact that the valve members 63 and 81 have both already been shifted to a maximum extent in the direction of movement of pin 78, no further movement of the pin and valves is possible. Consequently, arm 72 remains stationary, its hub slipping between the clutch members 73 and 74 of shaft 32.

It is to be noted that cam 31 has a very slight or gradual rise and can be moved through an arc of some 40 degrees for effecting desired slow feeding movement of the grinding wheel until the work is reduced to proper size. An adjustable stop 34 is preferably provided on the bed 10 to engage lever 33 and positively limit its movement and this movement of the cam in the feeding direction so that the operator can readily bring the handle up to this stop and know that the work has been ground to the prescribed size.

The actual work size is visibly indicated to the operator by the gage 35 whose hydraulic motor 38 is coupled with the conduits 64 and 84 so that the gage is automatically swung into and out of effective position simultaneously with the clamping and unclamping of the work piece. 70 Any slight size variance can therefore be compensated by adjustment of the work head as an entirety through the medium of lead screw 19 and pilot wheel 20.

The grinding having been completed, handle 33

is moved in a clockwise direction, initially effecting a slight movement of cam 31, permitting the wheel to retract slightly with respect to the work piece and effecting discontinuance of the grinding operation. Continued movement of the handle carries with it lever 17 and pin 18, releasing retaining pressure on valve 81 which is then urged outwardly by its spring 83 reversing the pressure and exhaust connections to motor 26. The conduit connections then existing, respects the valve 81, are thus shown in Figure 3.

With the parts thus adjusted, line 27 is connected through valve 81, conduit 85 and resistance 57, maintaining a pressure condition in the system to reservoir. The weight of the grinding head 22 is such as to bear against the piston, tending to force out the fluid at the upper portion thereof, the piston movement being further effected by introduction of pressure into the lower portion of cylinder 24 from line 28. This effects an immediate rapid retraction of the grinding wheel. Continued movement of lever 33 then positively, reversely shifts valve 63, introducing air or other fluid pressure into cylinder 38 for retraction of the gage as respects the work and simultaneously by the same pressure coupling moves piston 67, moving the chuck fingers 70 into work receiving position. It is to be noted that all of these movements take place during the initial clockwise movement of lever 33. This movement brings the termini of the two valve members against the adjustable stops 86 and 87, preventing further movement of the valves, and thus of rock arm 17, which, therefore, slips in a reverse direction on shaft 32 during the further movement of the lever necessary to return cam 31 to starting position.

As indicated by the several dotted line positions in Figure 3, the cyclic relation of the parts is preferably such that in initiating grinding action, a first 7 degrees movement of lever 33 operates the clamp cylinder for securing the work piece in position, and simultaneously therewith moves the visual or other gage device into contact with the work; the succeeding 7 degrees movement effects the rapid hydraulic infeed which has been shown as effective as respects the grinding wheel head, although it is to be understood that it is equally applicable to movement of the work head as an entirety under a similar piston control mechanism, if preferred. Continued movement of lever 33 directly effects the slow or relative feeding movement of grinding wheel and work as through the medium of the rise on cam 31, to any desired extent, an arc of movement of not over 40 degrees having so far been found entirely suitable.

As the extended movement of valves 63 and 81 are a direct function of the oscillation of rock arm 17, it will be apparent that on reverse movement of the parts from the grinding position, shown in Figure 7, to the initial position shown in Figures 3 and 4, valves 63 and 81 will be operated in reverse order but in accordance with similar increments of movement of shaft 32 and lever 33, the first operation being a slight separation of work and grinding wheel by initial reversal of cam 31 followed up by a movement of valve 81 under influence of its spring, causing rapid relative separation of work and grinding wheel, and thereafter a retraction of the gage and release of the work piece so that it may be withdrawn with one hand by the operator, while the continued retraction of the feed cam 31 is being effected by his other hand. In this man-

ner a sure and rapid clamping of the work, and advance of the work to grinding position is effected with a subsequent controlled feeding action, while on reversal of the parts appreciable time saving in production is effected by initiating the 5 retraction and release of the work immediately upon reversal of lever 33, in place of the cycle, necessitating first a slow retraction corresponding to the initial feed, and then subsequent rapid retraction and work release at the end of the 10 reverse movement of the feed control elements.

What is claimed is:

1. In a hydraulically operable machine tool having means for clamping the work and means for effecting relative approach and retraction of the work and tool, said means including hydraulic clamping and feeding mechanisms, a supplemental feed mechanism, control valves for said hydraulic mechanisms, and means for effecting shifting of said valves in inverse order during the 20 initial approach and initial retraction of work and tool, including a reversely actuatable control device having parts movable therewith reacting on said valves for determining the sequential shifting of said valves. 25

2. In a hydraulically operable machine tool having means for clamping the work and means for effecting relative approach and retraction of the work and tool, said means including hydraulic clamping and feeding mechanisms, a supplemental feed mechanism, control valves for said hydraulic mechanisms, and means for effecting shifting of said valves in inverse order during the initial approach and initial retraction of work and tool, including a reversely actuatable control device having parts movable therewith reacting on said valves for determining the sequential shifting of said valves, said control device including a manual actuator and means shiftable in accordance with movement of said 40 actuator for controlling the supplemental feed mechanism. 30

3. A machine of the character described including tool and work supports relatively movable toward and from each other, work clamp- 45 ing mechanism carried by the work support, hydraulic actuators for effecting the work clamping and said relative movement of the parts, control valves therefor, an oscillatable control member, a positive feed determinator shiftable there- 50 by, and an impositive control for the valve members movable with and relative to said oscillatable control. 55

4. A machine of the character described in- cluding tool and work supports relatively mov- 55 able toward and from each other, work clamping mechanism carried by the work support, hydraulic actuators for effecting the work clamping and said relative movement of the parts, control valves therefor, an oscillatable control member, 60 a positive feed determinator shiftable thereby, an impositive control for the valve members movable with and relative to said oscillatable control, and a friction slip coupling for effecting the impositive connection between the valve and 65 feed controls.

5. A control mechanism for a grinding ma- chine of the character described embodying a work support having a work clamping member, a tool support, and means for mounting said 70 work and tool supports for relative approach and retraction, said control mechanism including a primary device for effecting rapid approach and retraction of said parts, and a fine feed de- 75 vice having a progressive follow-up action as re-

spects the primary device, hydraulic mechanisms for actuation of the work clamp and said primary device, sequentially operable control valves for said hydraulic mechanisms, and an oscillatable control member for said valves and feed device, having means for effecting the actuation of said valves in inverse order at the initiation of each change in direction of oscillation thereof, whereby said hydraulic mechanisms are in each instance rendered effective prior to the operative effect of the feed mechanism.

6. The combination with a grinding machine including a bed or support, an oscillatable wheel head mounted thereon and means for effecting oscillation of the head in a direction toward and from a work piece including a hydraulically shiftable plunger and a cam member for co-acting with the plunger, of control mechanism for shifting of the wheel head including an oscillatable shaft supporting the cam, means for oscillating the shaft, a rock arm carried by the shaft, a slip coupling between the arm and shaft permitting overrunning of the shaft with respect to movement of the arm, and a control valve for the hydraulic plunger actuatable by the arm on initial oscillation of the shaft in either direction, whereby the hydraulic plunger anticipates the reaction of the cam on the wheel head.

7. A control mechanism for a grinding machine of the character described, which embodies a work head having a work clamp mechanism and a grinding wheel disposed in opposition to the work head for movement into an operative relation with respect thereto, said control mechanism including a manually oscillatable shaft, a rock arm carried by the shaft for movement therewith and relative thereto, a friction coupling between the arm and shaft whereby the arm will be actuated by the shaft on initial movement thereof in either direction, work clamping and rapid traverse mechanisms operable by the arm in reverse directions upon initial actuation of the shaft, and a feed determinator carried by the shaft and effective throughout an appreciable arc of oscillation thereof, whereby the feed determinator supplements the action of the rock arm control mechanism in either direction of oscillation of the shaft, substantially as and for the purpose described.

8. In a machine of the character described, the combination with a bed or support and a carriage mounted thereon for movement relative thereto, of means for effecting a controlled relative movement of said parts, including a hydraulically actuatable plunger member carried by one of said parts and an oscillatable cam carried by the other of said parts whereby oscillation of the cam will effect a direct mechanical shifting of the plunger, a source of hydraulic pressure, and a control member for determining the coupling of the hydraulic medium to the plunger for effecting shifting of the plunger with respect to its associated member, and connections between the cam and control member for actuating same to reverse the effect of the hydraulic actuating medium on the plunger at the inception of each oscillatory movement of the cam.

9. In a machine of the character described including tool and work supports relatively movable toward and from each other, work clamping mechanism carried by the work support, hy-

draulic actuators for effecting the work clamping and said relative movement of the parts, control valves therefor, an oscillatable control member, a mechanical feed determining cam operable by said control member, and an impositive control for the valve members movable with and relative to said feed control cam.

10. In a machine of the character described including tool and work supports relatively movable toward and from each other, work clamping mechanism carried by the work support, hydraulic actuators for effecting the work clamping and said relative movement of the parts, control valves therefor, an oscillatable control member, a mechanical feed determining cam operable by said control member, an impositive control for the valve members movable with and relative to said feed control cam, and connections between said cam and the hydraulic actuator for effecting relative movement of the parts, whereby during movement of the tool and work supports relatively toward each other, said cam will be additively effective as respects the hydraulic actuator in producing said movement.

11. A machine of the character described including tool and work supports relatively movable toward and from each other, work clamping mechanism carried by the work support, a rapid traverse mechanism for effecting rapid relative movement of the tool and work supports, a supplemental oscillatable control member for determining relative feeding movement of the supports, a source of hydraulic actuating medium, and means for determining the effect of the hydraulic medium on the work clamping and rapid traverse mechanisms including a pair of oppositely biased resiliently actuated valve members and a joint actuator coupled with the oscillatable control member and having a lost motion connection with both of said valve members, whereby said valve members will be shifted in a given direction in inverse order upon actuation of the control member.

12. A grinding machine including a bed or support, a wheelhead mounted thereon, a work support adapted to present a work piece in opposition to the wheelhead, hydraulically actuatable means for clamping the work piece on the work head, and means for hydraulically determining movement of the wheelhead in a direction toward and from the work support, a source of hydraulic medium for actuation of said clamping and head moving means, and means for controlling the coupling of the hydraulic medium with said parts for effecting predetermined cyclic operations thereof, including a pair of juxtaposed valve elements, resilient means oppositely urging said valve elements, means for limiting the movement of said valve elements in either direction, and an oscillatable actuator having lost motion connection with both of said valve elements, whereby in either direction of movement of the oscillatable control element, one of said valves will be resiliently urged with the control element to anticipate the movement of the other valve by the amount of said lost motion and the cyclic effect of the valves will be in inverse order as respects opposite directions of oscillation of the control member.

FREDERICK S. HAAS.
